UNITED STATES PATENT OFFICE

141,190

DESIGN FOR A COMBINED DISPENSING AND ARTICLE DISPLAY CABINET

Albert E. Aldridge, Elkins Park, Pa., assignor to Sun Oil Company, Philadelphia, Pa., a corporation of New Jersey

Application February 19, 1944, Serial No. 112,634

Term of patent 14 years

(Cl. D52—2)

To all whom it may concern:

Be it known that I, Albert E. Aldridge, a citizen of the United States, residing in Elkins Park, county of Montgomery, Commonwealth of Pennsylvania, have invented a new, original, and ornamental Design for a Combined Dispensing and Article Display Cabinet, of which the following is a specification, reference being had to the accompanying drawing, which forms a part thereof.

Figure 1 is a perspective view of a combined dispensing and article display cabinet embodying my new design.

Figure 2 is a cross-sectional view through the central part of Figure 1.

The dominant features of the design reside in the portions shown in full lines.

The opposite side of the cabinet is similar in appearance to the side shown.

I claim:

The ornamental design for a combined dispensing and article display cabinet, as shown and described.

ALBERT E. ALDRIDGE.
